UNITED STATES PATENT OFFICE.

GUSTAF HOLMGREN, OF BLOOMFIELD, NEW JERSEY.

ATOMIZER.

No. 853,455.

Specification of Letters Patent.

Patented May 14, 1907.

Application filed September 26, 1906. Serial No. 336,283.

To all whom it may concern:

Be it known that I, GUSTAF HOLMGREN, a citizen of the United States, and a resident of Bloomfield, in the county of Essex and State of New Jersey, have invented new and useful Improvements in Atomizers, of which the following is a specification.

My present invention relates to portable atomizing apparatus in general and particularly to devices for spraying of paint, varnish and the like. In devices of this character it is usual to supply a portable reservoir for the material to be sprayed or atomized to which is attached an appropriate nozzle and means for forcing the paint, varnish or other material out through said nozzle. These latter means preferably comprise tubes and passages disposed so as to lead compressed air in proper quantity into the reservoir over the material to be sprayed and at the same time to cause another portion of the air to create a suction near the orifice of the nozzle. By this means the air acts both by suction and pressure upon the paint or other material. It has been found in the use of this apparatus, that when it is desired to stop the jet of atomized material, the interruption does not occur with sufficient promptitude, and the material often drips from the nozzle tip, making use of the device disagreeable and dirty.

The present invention has for its principal object the suppression of this difficulty, by making the starting and stoppage of flow sudden and instantaneous.

Another object of my invention is the provision of a convenient means for use in connection with the apparatus aforesaid whereby the means for relieving pressure may be properly adjusted.

My invention further includes certain novel details hereinafter described and set forth in my claims.

I have illustrated one preferred form of this invention in the accompanying drawings, wherein

Figure 1 is a vertical section of a paint atomizer with certain parts shown in side elevation the better to illustrate my improvement; Fig. 2 is a vertical section of certain details and Fig. 3 is a plan view looking upward within the reservoir.

The container or reservoir is shown at 1, and is provided with a cover 2 secured thereto in a well known manner by straps 3 which also serve as a partial support for certain

other parts of the device. An elastic packing 4 under the cover 2 serves to make the closure air tight.

At 5 is shown the usual handle through which is led the tube 6 for supplying compressed air to the apparatus. A portion of this air passes directly out through the tube 6 to the nozzle 7, where it acts by suction to draw the material within the container up through the tube 8 and inner nozzle 9. The screw valve 10 is used to close the tube 8 more or less for purposes of regulation. Another portion of the compressed air is led through the tube 11 and an appropriate valve chamber 12 to the upper part of the reservoir 1, where it acts by pressure to expel the material within said reservoir.

The plunger valve whereby the flow of air is released or shut off is operated by the user's thumb which presses the knob 13 inward to release the air. The return movement of this valve for shutting off the air is automatic.

The apparatus thus far described is already known and forms no part of my present invention. As before stated, this apparatus is often subject to the disadvantages following from sluggish interruption of operation when the air is cut off, whence proceeds an objectionable dripping of the material down the sides of the device and onto surrounding objects. This dripping action is caused principally by the pressure of the volume of air remaining within the reservoir after the thumb valve is closed. This tends to expel a small amount of material through the tubes 8 and 9. In my improved device, therefore, I obviate this difficulty by supplying an additional opening from the upper part of the reservoir 1 to the outer air, and a relief valve is used whereby, during operation, this opening is kept closed, but by means of which it may be opened each time the air is cut off. My broad invention covers the use of this opening and valve however operated, but I prefer to arrange the same so that its operation shall be automatic and so that the movement of the air cut-off one way or the other shall of itself cause appropriate action of the relief valve. While this may be accomplished in a variety of ways without departing from the scope of this invention, I prefer the construction herein illustrated, wherein an opening 14 in the cover 2 is controlled by a slide valve 15 having an appro-

priate opening 16 and connected to the cut-off valve by means of a rod or wire 17. The rod 17 is preferably connected to the slide valve 15 by an easily detachable connection, as by means of the hook 18, passing through an appropriate opening in the slide valve.

In Fig. 1 is shown the position of the parts when the air is cut off, while Fig. 2 shows their position during operation of the atomizer. As shown in the latter position, the relief opening 14 is covered by the slide valve so that the compressed air which enters the reservoir, being confined, acts efficiently in expelling the paint or other material. On releasing the thumb piece 13, however, the cut-off valve moves automatically into the position shown in Fig. 1, cutting off access of compressed air to the device. At the same time the rod 17 draws the slide valve 15 to the right in Fig. 2 and a clear opening to the outer air is provided by the apertures 14 and 16 being made to register. This at once relieves the pressure of air over the material in the reservoir and it is thus prevented from continuing to expel surplus paint. Moreover, if this relief is made sufficiently sudden a slight inward suction is produced at the nozzle tip, whereby adhering material is drawn inward and the end of the nozzle is left absolutely clean. The sudden exit of air through the relief opening is apt to carry with it a little of the paint or other material, and for this reason I prefer to provide a small guard or hood 19 on the slide 15 covering the opening 16 and having a lateral opening only. This prevents the paint from being thrown onto the user when the relief valve is opened. In order to regulate at will the suddenness of the air relief I provide means adjustable at will for changing the size of the available opening. These means may take a variety of forms but I prefer the simple device shown in the drawings, wherein a flat circular plate 20 is placed against the under surface of the cover 2 and is provided with an aperture 21 adapted to register with the relief opening 14. By turning the plate 20, the relative positions of the openings 21 and 14 may be changed so as to modify the available vent. In the preferred form shown, the ring 20 is fastened in place by a flat cross plate 22 which is fixed to the cover 2 at the center of the ring by a thumb screw 23. The opening 21 is made in this cross plate. The thumb screw is used to fix the plate 20 in any desired position after proper adjustment of the opening 21.

Various changes may be made in the parts of this device without departing from the scope of my invention and I am not to be limited to the details herein shown and described.

What I claim is—

1. An atomizing apparatus, comprising a reservoir, means for forcing material in a

spray therefrom and a relief valve on said reservoir.

2. An atomizing apparatus, comprising a reservoir, means for forcing material in a spray therefrom, a cut off valve controlling 70 said means and a relief valve on said reservoir adapted to operate simultaneously with said cut off valve.

3. An atomizing apparatus, comprising a reservoir, means for forcing material in a 75 spray therefrom, a cut off valve controlling said means, a relief valve on said reservoir and a mechanical connection between said cut off valve and said relief valve, whereby they are made to operate simultaneously. 80

4. In atomizing apparatus comprising a reservoir, means for forcing material in a spray therefrom, a cut off valve and a relief valve adapted to close automatically when the cut off valve opens and vice versa. 85

5. An atomizing apparatus comprising a reservoir, means for forcing material in a spray therefrom, and a relief valve on said reservoir having an adjustable opening.

6. An atomizing apparatus comprising a 90 reservoir, a relief opening in its top, a revolute plate placed against said top and having an opening adapted to register with said relief opening and means for securing said plate in various positions at will. 95

7. An atomizing apparatus comprising a reservoir having a relief opening in its top, a revolute ring having a perforated cross plate and fitting against said top and a thumb screw passing through said cross plate for securing it in any desired position. 100

8. An atomizing apparatus comprising a reservoir having a relief opening in its top, a slide valve over said opening and a means for operating said slide valve. 105

9. An atomizing apparatus comprising a reservoir having a relief opening in its top, a slide valve over said opening and a thumb piece for operating said valve.

10. An atomizing apparatus comprising a 110 reservoir having a relief opening, means for forcing material out of said reservoir, a cut off valve for said means, a slide valve over said relief opening and a mechanical connection between said slide valve and said cut off. 115

11. An atomizing apparatus comprising a reservoir having a relief opening, means for forcing material out of said reservoir, a cut off valve for said means, a thumb piece for operating said cut off, a slide valve over said 120 relief opening and a rod connecting said slide valve with said thumb piece.

12. An atomizing apparatus comprising a reservoir having a relief opening and a slide valve over said opening provided with a hood. 125

13. An atomizing apparatus comprising a reservoir, a cut-off valve for the pressure agent, and a relief valve for the release of said agent from the reservoir, when the cut off valve is closed. 130

14. An atomizing apparatus comprising a reservoir, a cut-off valve for the pressure agent, and a relief valve for the release of said agent from the reservoir, the relief valve being open when the cut off valve is closed, and closed when the cut off valve is open.

5 In testimony whereof, I have signed my

name to this specification, in the presence of two subscribing witnesses.
